UNITED STATES PATENT OFFICE.

JULIUS GUILDENSTINE, OF NEW YORK, N. Y., ASSIGNOR TO ARTHUR M.
AND ALSON E. BARNHART, OF CHICAGO, ILLINOIS.

DESIGN FOR A FONT OF PRINTING-TYPE.

SPECIFICATION forming part of Design No. 15,787, dated February 10, 1885.

Application filed January 12, 1885. Term of patent 14 years.

To all whom it may concern:

Be it known that I, JULIUS GUILDENSTINE, a citizen of the United States, residing in the city of New York, county of New York, and State of New York, have invented and produced a new and original Design for a Font of Printing-Types, of which the following is a specification, reference being had to the accompanying typographical illustration, forming a part hereof.

The character of this letter is of a semi-Runic style; and it consists of capitals, lower-case, figures, and points. The main feature of this letter is shown in its peculiar cut, the upper half of capitals A B C D E F G H I J K L M N P R T U V W X Y being of the Runic style, while the lower half is strictly Gothic. The same peculiarity is again shown

in lower-case b d f h i j k l m n p r u v w x y z. The perpendicular strokes of capitals F H I K M N P R T Y and lower-case f m n p q r y extend below the line of the other letters, and are mitered at the bottom from right to left. Capitals C, D, O, Q, and U have a round dot in center of each, while capitals J L V W X Y have dot on outside of each. Capital T has two dots, one on either side of perpendicular stroke.

I claim—

The design for a font of printing-types, as described, and shown in the accompanying illustration.

JULIUS GUILDENSTINE.
